UNITED STATES PATENT OFFICE

LOUIS N. PODELL, OF MILWAUKEE, WISCONSIN

DESIGN FOR A TEETHING DEVICE

Application filed October 23, 1931. Serial No. 41,501. Term of patent 7 years.

To all whom it may concern:

Be it known that I, LOUIS N. PODELL, a citizen of the United States, residing at Milwaukee, in the county of Milwaukee and State of Wisconsin, have invented the new, original, and ornamental Design for Teething Devices, of which the following is a specification, reference being had to the accompanying drawing, forming part thereof.

Figure 1 is a plan view of a teething device showing my new design.

Figure 2 is a side elevation of Figure 1.
Figure 3 is a front elevation of Figure 1.

I claim:

The ornamental design for a teething device substantially as shown.
In testimony whereof, I affix my signature at 6083 Plankinton Building, Milwaukee, Wisconsin.

LOUIS N. PODELL.
